Specification for Design.

Patented Aug. 1, 1922.

Application filed April 1, 1922. Serial No. 1,496. Term of patent 7 years.

To all whom it may concern:

Be it known that I, WILLIAM H. POWERS, a citizen of the United States, residing at 3441 North Harding Avenue, Chicago, in the county of Cook and State of Illinois, have invented a new, original, and ornamental Design for a Toy Dog, of which the following is a specification, reference being had to the accompanying drawing, forming part thereof.

I claim:

The ornamental design for a toy dog substantially as shown.

WILLIAM H. POWERS.
